(57) **CLAIM**

The ornamental design for a display screen or portion thereof with animated graphical user interface as shown and described.

DESCRIPTION

FIG. 1 is a front view of a display screen or portion thereof with animated graphical user interface showing a first image of the claimed design; and, FIG. 2 is a second image thereof.

The outer broken lines in the figures show a display screen or portion thereof, and form no part of the claimed design. The other broken lines in the figures show portions of the animated graphical user interface that form no part of the claimed design.

The appearance of the animated image sequentially transitions between the images shown in FIGS. 1-2. The process or period in which one image transitions to another forms no part of the claimed design.

The figures are illustrated to show contrasting appearance. Areas of the display screen or portion thereof with animated graphical user interface that appear in different shades of gray represent areas with contrasting appearances.

The figures are lined with horizontal, curved, and cross-hatched lines to show the placement of first, second, and third visual effects, respectively. The figures are not lined for any particular color, and the horizontal, curved, and cross-hatched lines form no part of the claimed design. When the display screen or portion thereof moves, the animated graphical user interface shows the placement of the visual effects as shown in the figures.
